UNITED STATES PATENT OFFICE.

EFISIO SIMOLA, OF BERWIND, COLORADO.

DESIGN FOR SURFACE ORNAMENTATION FOR A COCOANUT-SHELL OR SIMILAR ARTICLE.

55,721.

Specification for Design.

Patented July 6, 1920.

Application filed September 22, 1919. Serial No. 325,557. Term of patent 3½ years.

To all whom it may concern:

Be it known that I, EFISIO SIMOLA, a citizen of the Kingdom of Italy, residing at Berwind, in the county of Las Animas and State of Colorado, have invented a new, original, and ornamental Design for Surface Ornamentation for a Cocoanut-Shell or Similar Article, of which the following is a specification, reference being had to the accompanying drawing, forming part thereof.

Figures 1, 2, 4 and 5 are side elevations of a cocoanut shell embodying my design, and, Figs. 3 and 6 are end views of the same.

I claim:

The ornamental design for surface ornamentation for a cocoanut shell or similar article, as shown.

EFISIO SIMOLA.
